United States Patent Office.

JOHN COLLINS, JR., AND NICHOLAS R. NIXON, OF RICHMOND, INDIANA,
ASSIGNORS TO N. R. NIXON, THOMAS NIXON, AND ALLAN T. BENNETT.

Letters Patent No. 73,695, dated January 28, 1868.

IMPROVEMENT IN RAG-CUTTING MACHINES.

The Schedule referred to in these Letters Patent and making part of the same.

TO ALL WHOM IT MAY CONCERN:

Be it known that we, JOHN COLLINS, Jr., and NICHOLAS R. NIXON, both of Richmond, in the county of Wayne, and State of Indiana, have invented a certain new and useful Seaming and Rag-Cutting Machine; and we do hereby declare that the following is a full, clear, and exact description of the construction and operation of the same, reference being had to the annexed drawings, making part of this specification, in which—

Figure 1 is a top view with the guard on.

Figure 2 is a sectional elevation through the line *q q* in fig. 1.

Figure 3 is a sectional elevation through the line *h h* in fig. 1.

Heretofore the operation of seaming rags intended for shoddy or paper was slow and tedious, requiring much care and skill, the operation having to be performed by hand, with ordinary scissors, or by pulling the rags against a scythe-blade.

The object of our invention is to seam rags, whether to be manufactured into shoddy, or fine paper, or other purpose, with less labor, less skill, and more rapidly than it was heretofore done.

To enable others skilled in the art to make and use our invention, we will proceed to describe its construction and operation with reference to the drawings.

Similar letters of reference refer to similar parts of our machine in the different drawings.

D D is the framework on which our machine is built. B B is the top of the frame, and through which the cutters act, as seen in fig. 2. e e is the arbor running through the frame, and on which the cutters are attached. A A A is the guard placed over the cutters on the table. n n n are cutters or knives for cutting or seaming the rags. They are thin strips of steel, arranged as shown on the arbor, or on a separate piece of metal fitted on to the arbor. The arbor runs through the framework about four inches from the surface of table B B, and the cutters n n n are of such length that they extend above the table three inches. The hole in the table through which the cutters act is just sufficiently large for the cutters to play through freely without touching the table, and no larger. The guard A A is of the shape shown in the drawings, fig. 2. Said guard is made of heavy tin or brass, and its width is to be just sufficient for the cutters to act freely in, and no more, as shown at A, fig. 3. The space at a a, fig. 2, which is a few inches on either side of where the cutters pass the table in the operation of cutting or seaming the rags, and is to be of less height than the thickness of the operator's smallest finger, but within that limit, may be large enough to permit any required number or thickness of rags to pass through, that is, between the table B B and its edges. The guard is to be fastened to the table B B by bolts or screws, as seen in fig. 1. The cutters may receive their motion from the pulley M, and be worked by treadle, horse, or steam-power. The guard A A, when constructed as is herein shown and specified, is an absolute protection from the cutters n n to the fingers of the operator.

When the machine is in motion, the cutters moving towards a a, the operator places the rags to be seamed, of any desired thickness or number of layers, upon the table A A, but not of greater thickness than the space between the guard and the table at a a. The rags are then drawn against the cutters in the line in which he desires the rags to be cut or seamed, and, as the rags are drawn past the cutters, they will separate or seam them, and the refuse may be drawn off at the left side and the good rags at the right side, or the reverse.

Having thus described our invention, what we claim as new, and desire to secure by Letters Patent, is—

The combination of the knives n n n, arranged upon the shaft e with the guard-plate A, all constructed and operating substantially as and for the purposes described.

JOHN COLLINS, JR.,
N. R. NIXON.
